UNITED STATES PATENT OFFICE.

WILLIAM MOORE, OF KOKOMO, INDIANA.

GAS OR OIL WELL TUBING.

SPECIFICATION forming part of Letters Patent No. 554,076, dated February 4, 1896.

Application filed February 18, 1895. Serial No. 538,782. (No model.)

To all whom it may concern:

Be it known that I, WILLIAM MOORE, a citizen of the United States, residing at Kokomo, in the county of Howard and State of Indiana, have invented certain new and useful Improvements in Gas or Oil Well Tubing; and I do hereby declare the following to be a full, clear, and exact description of the invention, such as will enable others skilled in the art to

10 which it appertains to make and use the same.

The object of my invention is to utilize the pressure of natural gas in gas-wells for the purpose of bringing to the surface and discharging the heavier liquids, such as water and oil, which underlie the volume of gas at the bottom of the well and which follow the gas into the tubes so as to eventually choke up the outlet and destroy the utility of the well. This I accomplish by a novel construction and arrangement of a series of valves and checks in the well-tubing whereby any one of the valves can be operated upon separately from the top of the well.

A further object of the invention is to increase the flow of gas and prolong the life of the well, but in order to understand the nature of my invention fully it is necessary that the usual and general practice of drilling gas-wells be explained.

30 Natural gas in the Ohio and Indiana fields is found in what is called "Trenton rock," an open porous formation underlying a sealed covering impervious to the passage of gas and at an average depth of one thousand feet from the surface of the earth. The pressure of the gas thus contained within the earth will average about three hundred pounds to the square inch. The Trenton-rock formation is of great depth and is more or less porous throughout.

40 The upper part of it, next to the impervious strata spoken of, contains the fluid gas and the lower portion of the Trenton rock contains generally oil or water, or both. A vertical column of this oil or water one thousand feet high gives a pressure of four hundred and fifty pounds to the square inch at the bottom of the well, which is about one hundred and fifty pounds more to the square inch than the gas-pressure at that point. 45 Hence the pressure of the gas is insufficient to carry out these liquids and the result is that the water and oil will fill up six hundred or

seven hundred feet of the vertical tubing, balancing the gas-pressure, and the well ceases to flow gas. When this condition occurs the well is said to be "drowned out," and hundreds of wells are now in that condition throughout the gas-fields of Ohio and Indiana. Were it not for the accumulation of water in the wells they would continue to flow gas for a much longer period of time.

In the drilling of gas-wells the usual way is to drill into the Trenton rock only a short distance, great care being taken not to get down to the water-line, which in some localities is only a short distance from the commencement of the rock. Should the well reach the water-line it is considered of small value because the water and gas having the same pressure to the square inch the water will commence at once to feed into the tubing of the well and if not carried out by the gas will continue to rise six hundred or seven hundred feet until the weight of the column of water equals the pressure of the gas and the column at such a height heads off the flowing of the gas.

The new method of equipping a well with my system of valves and tubing is to drill down some distance into the water or oil bearing portion of the Trenton rock, down much deeper than the general practice, and then inserting my improved system of tubing and valves, whereby the water or oil which will be admitted at the bottom will be started in its discharge from the mouth of the well by a proper manipulation of a series of valves supplied at intervals in the length of the tubing. Upon the removal of the accumulation of water or oil in the tubing the water and oil in the vicinity of the well will flow in by pressure and gravitation to take its place, thereby emptying the pores of the rock down to a much greater depth than formerly and affording an increased outlet for the gas from the Trenton rock into the tubing, whereby the flow of gas from the well will be largely increased. Hence it is self-evident that by utilizing the stored energy of the gas through mechanical appliances it is possible to exhaust the liquids underlying the gas, and not only prevent the drowning out of the gas, but increase its flow and prolong the life of the well.

I accomplish the objects of this invention

by the mechanism illustrated in the accompanying drawings, in which—

Figure 1 is a view in vertical section of a portion of the earth's crust, showing the average rock formation in the gas-producing district of Indiana. The view shows a gas-well equipped with my improved well-tubing and illustrates diagrammatically the condition of the Trenton limestone around the bottom of the well after the water has been extracted by my mechanism. Several sections of the strata above Trenton rock are shown as broken away and removed in order to shorten the drawing to bring it within the compass of the sheet; but no material parts are omitted. Fig. 2 is a detail in like vertical section of the upper part of the well and illustrates diagrammatically the saturated condition of the rock above the water-line in a well which has been drowned out by this encroachment of the oil or water. In this view the tubing and well end at a point above the water-line in the manner required in the equipment of wells prior to my invention. Fig. 3 is a detail in elevation and partially in vertical section of the tubing at the top of the well, showing the lever by which the central tube is manipulated in opening and closing the series of valves in the tube. The figure also shows the receiver into which the gas, oil, and water discharges and in which the gas is separated from all foreign ingredients and dried before its delivery to the distributing-main. Fig. 4 is an enlarged detail of the anchor at the bottom of the well by which the bottom of the middle tube is held from revolving when the upper section of the tube is rotated to operate some of the valves. The dotted lines indicate the position of the parts before the anchor-bars are forced into locking position. Fig. 5 is a view in side elevation of a check-valve which forms the lowest one in the series of valves used in my improved construction; and Fig. 6 is a vertical section of same on the dotted line 6 6, Fig. 5. Fig. 7 is a slip-valve by means of which outside gas can be admitted at that point when the valve is open, and Fig. 8 is a vertical section of same on the lines 8 8 of Fig. 7. Fig. 9 is a view in elevation of a screw-valve for the same purpose as the valve shown in Fig. 7, and Fig. 10 is a vertical section of same on the line 10 10 of Fig. 9. Fig. 11 is a slip-valve similar to that shown in Fig. 7 with the addition of a locking-notch whereby the two parts of the tube will be locked together when in their closed position, and Fig. 12 is a vertical section on the line 12 12 of Fig. 11. Fig. 13 is a transverse section of the valve shown in Fig. 6 and is taken on the line 13 13 of Fig. 6. The direction of view in all of the sectional views is indicated by the arrows in the several elevations. The raised or open adjustment of the valve in Fig. 11 is indicated by the dotted lines in that figure.

Similar letters refer to like parts throughout the several views of the drawings.

Referring to Fig. 1, A represents a well which is drilled down through many strata of different formations of rocks to a depth varying from one thousand to three thousand feet into a porous gas-bearing formation A', the under portion of which is filled with water or oil. The dotted line I shows the natural level of the liquids contained in the rock, and, as previously stated, in the usual way of drilling great caution is used not to drill below this water-line for fear of spoiling the well.

Under the natural law of gravitation and the equalized pressure of the gas above it the heavier fluid seeks a level conforming to the curvature of the earth in obedience to the same law that compels water to seek its level under the equalized pressure of the atmosphere above it, and when the gas is flowing from the well the uniform gas-pressure in the rock which maintained or forced the water down to a common level is reduced in the vicinity of the well and the liquid commences to rise in the gas-bearing rock adjacent to the well in the same manner that water follows up the vacuum in a pump. This condition is illustrated in Fig. 3. As this reduced pressure is maintained by the continual flowing of the gas, the liquids in the pores of the rock flow in the direction of the well, gradually filling up the rock until the gas is shut back from the well. The water continues to flow into the well until the hydrostatic pressure of the column at the bottom is equal to the gas-pressure in the rock. The wells are then abandoned and new ones drilled only a short distance from the old and which give a large flow of gas for a short time and are then drowned out in the same way as the first; but with my improved system of tubing these wells would continue to flow gas for a long period of time and with an increasing flow, for the reason that I remove the water from the pores of the rock and by so doing extend the possible area for the accumulation and free passage of the gas in the rock to a much greater depth than before, and by so doing I open up a much larger area of gas-bearing rock to supply the well.

B in the drawings represents the top outer casing, which extends only through the top drift for the purpose of excluding the water which usually abounds therein. B' represents the original tubing used in the well before it was drowned out, and C is the tubing which I will employ expressly for the purposes of my invention, and which will be of sufficiently smaller diameter than the tubing B' to permit of its being inserted within the tubing B'. The escape of gas around the tube C will be prevented by means of a suitable packing c at the top of the well and which may be of any desired or usual construction. A packing b is always placed between the outside of the tube B' and the sides of the well so as to prevent the escape of gas around the outside of the tube B'. This packer is generally placed in the impervious formation im-

mediately above the Trenton limestone, as shown in Fig. 1. Openings b' and b^2 are provided through the tubing B' for the entrance of the gas. The lower end of the tube C terminates with the wedge C' . This wedge is slotted vertically to receive the pin c' , which pin is also projected through openings in the U -shaped anchor-bars c^2 . The ends of the pin c' are sufficiently expanded to prevent their being drawn through the openings in the anchor-bars, and the purpose of the pin is to form a guide for the wedge and to also hold the bars up in proper position. When the tube is deposited into the well the wedge will be forced between the anchor-bars and the bars spread apart until the ends are impinged against the side of the tube B' , thereby holding the wedge in a firm and immovable manner and also preventing the attached tube from turning. The lower end of the tube C is perforated to allow the free access of gas and water into said tube.

At a suitable distance above the lower end of the tube C is a check-valve D , (shown in Figs. 5 and 6 and in cross-section in Fig. 13,) which will allow water, oil and gas to pass freely in an upward direction through the tube, but will prevent their return. The construction and operation will be clearly understood from the drawings.

At suitable intervals throughout the length of the tube C —that is, at distances of from one hundred to three hundred feet apart according to circumstances—I provide valves, each of which when opened will admit gas from the tube B' into the tube C . These valves will be constructed in such a manner that by the proper manipulation of the tube C by the operator at the mouth of the well the valves, beginning with the top one, can be opened successively so as to admit the gas at that point. The column of water above the first valve will be small enough in quantity to enable the pressure of the gas to blow it out of the tube, after which the valve will be closed and the one next below will be opened and the body of water in the tube between the first and second valves will be removed by the pressure of the gas in like manner. This operation will be continued with the remaining lower valves until the tube is emptied of whatever water or oil may have accumulated therein. E represents the lower sliding valve which is represented in enlarged detail in Figs. 7 and 8. The upper portion, e , is screwed onto the end of the tube C and is provided with a suitable opening or bore to receive the reduced upper end of the lower section, e' , of the valve. A stud-pin e^2 integral with or screwed into the part e' is projected into a vertical slot through the wall of the section e , as clearly shown in the drawings. The part e is provided with the openings e^3 , through which the gas in the tube B' will be admitted to the tube C when the valve is open, but which will be closed by the inside section, e' , when the valve is closed. Fig. 8 shows the valve

in closed position. The extent to which the valve can be opened will be controlled by the length of the slot to receive the pin e^2 .

F represents the next higher valve which is shown in enlarged scale in Figs. 9 and 10. The valve differs from the valve E only in the manner in which the upper and lower sections of the valve are connected and are adjusted with relation to each other. In the valve F the two parts are provided with left-handed threads f and the valve is opened and closed by giving the upper tubing C a rotary movement.

G is the uppermost one of the valves and is similar to the valve E , the only point of difference being that the vertical slot in the outer section to receive the pin is provided with a notch g , whereby the valve is locked against the vertical movement by which the valve is operated and the notch is on that side of the vertical slot whereby the rotary movement required to unlock the valve will be in the direction opposite to that required to open the valve F . The dotted lines in Fig. 11 represent the open position of the valve.

H is a lever fastened to the tube C at the top of the well, whereby the tube can be rotated in the manner required to operate the valves F and G , and I is a set-screw by which the tube may be moved longitudinally in operating the valves E and G . It is not, however, desired to limit the invention to the exact mechanism as here shown for operating the tube C in opening and closing the valves.

The tube C will empty into the receiver H' in the manner as shown in Fig. 2 and will be provided with the stop-cock C^3 of usual construction. The tube is also provided with an outlet C^7 into the open air, and the stop-cock C^5 will allow the discharge through the pipe C^7 to be controlled. The receiver may be of any suitable construction that will remove the water or oil from the gas, preferably such as is secured to me by former patents, and now in general use throughout the gas-field.

From the above description it is believed a better understanding of the invention and its objects has been obtained, and I will now give a more detailed description of its operation and purposes. If a well was closed in at the top and no gas allowed to be drawn from it, the gas-pressure in the rock in the vicinity of the well would become equalized the same as it was before the well was drilled, and the water would again find its level in the rock by gravitation and would be up to the dotted line I in Fig. 1. The lower end of the tubing would be entirely submerged in water or oil. No gas could enter the tubing at the lower end. Nothing but a solid column of water or oil would be admitted, and that would be under a pressure of three hundred pounds to the square inch, a pressure sufficient to drive a column of water up the tubing six hundred and eighty-two feet to the line marked L , lacking some three hundred feet of reaching the top of the well. The well would stand

sealed at that point, yet an immense quantity of gas would be retained in the rock. As the tube B' is closed at the top, it will be filled with gas from the rock through the openings 5 b² below the packing b at a rock-pressure of three hundred pounds to the square inch. All of the water or oil in the inner tube C and above the valve D will be held from returning by said valve, and in order to remove the 10 water or oil I will close the stop-cock C³ in the pipe leading to the receiver H at the top of the well and open the stop-cock C⁵ for an outward discharge to atmospheric pressure. I then open the valve G, admitting gas into 15 the tubing C at three hundred pounds pressure, which will throw out all of the water above the point of ingress of the gas, and for awhile the water-pressure will continue to drive the water up to that point and the gas 20 entering through the openings in the valve will keep up a constant flow. I then close the valve G and open the next lower valve F, whereupon the gas entering the tube C will throw the column of water out from this point. 25 Then closing it, I open valve E. This last operation will exhaust the water from the well until the gas and water will both enter the tubing at the bottom of the well, and when all of the valves E, F, and G are closed the 30 well will continue to flow a mixture of water or oil and gas. I then close the cock C⁵ and open the cock C³ to the receiver for separating the gas from the oil and water.

When the rock gives a very large quantity 35 of water the valves E and F may be left a little open to assist in raising the water along the line of tubing.

M is a pipe leading from the receiver H' and emptying into the tube B'. It has the stop 40 cock or valve m. The purpose of this pipe is to supply the tubing B' with high-pressure gas from other wells when no gas in the rock below enters the well. The high-pressure gas thus supplied will empty the tube C in the 45 same manner as above described.

The valves in the tube C are independent of each other, and the number required in any well will depend upon its depth and on the gas-pressure in the rock. The average well in 50 Indiana would require but two of the valves and the check, and in some cases only one valve and the check. Where there is a large flow of gas the inner tubing should gradually increase in size as it nears the top of the well, 55 and the valves in many cases should remain partially open when a large flow of gas is desired.

It is not desired in this invention to limit the construction of the valves D, E, F, and G to that here shown and described, as other forms equally as effective might be employed; but

What I do claim, and wish to secure by Letters Patent of the United States, is—

1. In the working of natural-gas wells, the method of emptying a gas-well of the column of liquids, oil or water, elevated in said well

by the pressure of the gas confined in the gas-bearing rock or stratum, which consists in conveying, by a conduit independent of said well, gas from said stratum to different portions of the well and admitting it into said column at different points thereof in succession, beginning at a point such that the pressure of the gas will elevate and discharge the 75 portion of the column above the point of admission, and when the level of the column has been reduced below said point, then at the next lower level, and so on, and at each operation preventing the downward return 80 of the column, substantially as described.

2. In a gas-well, the combination of a tube reaching from the top to the bottom of the well, provided with a plurality of valved openings, and an independent conduit extending thereto from the gas-bearing strata around the bottom of the well, said valves being operatively connected with each other to the top of the well whereby they may be operated therefrom to open or close the same, 90 substantially as described.

3. In a gas-well, the combination of a tube reaching from the top to the bottom of the well, a packing around the tube above the gas-producing rock whereby a volume of high-pressure gas will be maintained around the tubing, a check-valve in the tube near the bottom of the well, an opening in the tube at a suitable interval between the check-valve and the top of the well for the admission of 100 high-pressure gas into the tube, an independent conduit from said opening to the gas-bearing strata below said packing and a closure for said opening operatively connected with the top of the well, substantially as described.

4. In a gas-well, the combination of a tube reaching from the top to the bottom of the well, a packing around the tube whereby a volume of high-pressure gas will be maintained around the tubing, a check-valve in the tube near the bottom of the well, openings in the tube at suitable intervals between the check-valve and the top of the well for the admission of high-pressure gas into the 115 tube, an independent conduit from said openings to the gas-bearing strata below said packing, and closures for said openings operatively connected with the top of the well, substantially as described.

5. Tubing for gas or oil wells having a plurality of valves for the admission of high-pressure gas, said valves being operated by the movement of the upper tubing, said movement being in a different direction for each 125 of the different valves, as rotary, longitudinal, or combined rotary and longitudinal, substantially as described.

6. In a gas-well, the combination with an outer tube, of an inner tube constructed of a 130 series of sections connected with each other so as to have limited relative diverse movements at these connections, an anchor attached to said inner tube, valved openings

located at said connections in the side of said inner tube and leading from the outer tube and adapted to be operated by the particular relative movement to be given to said connections, and means to operate said valved openings from the top of the well, substantially as described.

7. In a gas-well, the combination with an outer tube, of an inner tube having a series of valves, arranged at intervals, leading from said outer tube thereinto through its sides,

all of said valves being controlled from above by one connecting mechanism and each being operated only when said controlling mechanism is given a particular motion adapted to move said valve, substantially as described.

In testimony whereof I affix my signature in presence of two witnesses.

WILLIAM MOORE.

Witnesses:

JOSEPH A. MINTURN,
F. W. WOERNER.

It is hereby certified that in Letters Patent No. 554,076, granted February 4, 1896, upon the application of William Moore, of Kokomo, Indiana, for an improvement in "Gas or Oil Well Tubing," errors appear requiring correction, as follows: In line 93, page 2, "Fig. 3" should read *Fig. 2*, and in line 103, page 3, "Fig. 2" should read *Fig. 3*; and that the said Letters Patent should be read with these corrections therein that the same may conform to the record of the case in the Patent Office.

Signed, countersigned, and sealed this 31st day of March, A. D. 1896.
